UNITED STATES PATENT OFFICE.

TULLY LA TESSA, OF CHICAGO, ILLINOIS, ASSIGNOR TO H. A. BEST LAMP COMPANY, A CORPORATION OF ILLINOIS.

DESIGN FOR A BASE FOR A FLOOR LAMP.

Application filed January 19, 1928. Serial No. 24,924. Term of patent 3½ years.

To all whom it may concern:

Be it known that I, TULLY LA TESSA, a citizen of the United States, residing in Chicago, county of Cook, and State of Illinois, have invented a new, original, and ornamental Design for a Base for a Floor Lamp, of which the following is a specification, reference being had to the accompanying drawing, forming part thereof.

In the drawing, the figure represents an outline plan view of a base for a floor lamp with a section of the same shown in complete form, it being understood that the remaining part of the figure, which is shown merely in outline, is a mere repetition of the part shown more fully.

I claim:

The ornamental design for a base for a floor lamp, as shown.

TULLY LA TESSA.
